3,350,758 WRAP REMOVER

Beryl A. Boggs, Chester, Va., assignor to Allied Chemical Corporation, New York, N.Y., a corporation of New York

Filed Feb. 23, 1966, Ser. No. 529,555
2 Claims. (Cl. 28—20)

This invention relates to an apparatus for removing wraps from moving rolls. More particularly, this invention relates to an apparatus for removing wraps from rolls used in fiber drawing operations. These rolls are referred to hereinafter as "draw rolls."

In fiber drawing operations imparting tensile strength to a yarn the yarn is passed over a feed roll, over a separator roll and over a draw roll revolving at a greater rate than the feed roll causing tension in the yarn. At any stage when the yarn is under tension it can break particularly if processing conditions for the yarn preparation were not sufficiently uniform. If the yarn breaks between the draw roll and a winder used for winding the yarn onto a bobbin or the like the newly formed head wraps around the draw roll several times in an uneven manner requiring removal of these wraps. It is standard practice to remove the yarn wraps from the draw rolls with the draw roll in operation and various devices are currently in use many of which entail danger to the operator.

It is an object of this invention to provide an apparatus for removing yarn wraps from rolls particularly rolls used in yarn drawing operations.

It is another object of this invention to provide an apparatus for removing yarn wraps from rolls used in yarn drawing operations which can be utilized without stopping the roll rotation without danger to the operator.

These and other objects and advantages of my invention will become apparent from the following description and claims.

This invention contemplates an apparatus for removing wraps from a revolving roll which comprises a cylinder open at at least one end and adaptable to envelop a roll said cylinder defining window on its side, a scraping means longitudinally slidably positioned on said cylinder and rotatable about its own longitudinal axis said means having a protruding element adaptable to pass through said window and remove said wraps from said roll into said cylinder and guide means disposed on the surface of said cylinder for positively positioning said cylinder against rotation due to movement of said roll.

In a particularly desirable embodiment of this invention the scraping means is a rod maintained within a tube rigidly affixed substantially parallel to the surface of the cylinder said rod being slidable through said tube and rotatable about its own longitudinal axis; said protruding element is a rigid material such as wood, plastic, metal, or laminated composite structure, said material, where it contacts said roll, being softer than the surface of said roll; said cylinder is provided with a handle affixed to a plate covering the end of said cylinder opposite the end which envelops the roll; said guide is an annular tube adapted to snugly accommodate a rigid pin adjacent said roll.

In order to better understand the instant invention, reference is made to the accompanying drawings in which:

FIGURE 1 is a side elevation of the apparatus of my invention on the left in relationship to a typical roll assembly on the right for drawing yarn;

FIGURE 2 is a side elevation of the apparatus of my invention in operating position enveloping the roll and positively positioned against rotation due to movement of the roll;

FIGURE 3 is an end view of the apparatus of my invention and

2

FIGURE 4 is a perspective view of the apparatus of my invention.

Referring now to the figures, wrap remover 1 comprises cylinder 2 having on its surface an open window 4. The cylinder is open at end 6 so that cylinder 2 can envelop roll 8 about which are yarn wraps 10. Roll 8 having rotatable flange 12 is mounted on mounting 14 onto which are also fixed rotatable separator roll 16 and pin 18. Annular tube 20 is rigidly secured to the surface of cylinder 2 and adapted to accommodate pin 18 therein snugly as shown in FIGURE 2. Opposite open end 6 of cylinder 2 is rigidly affixed cover 22 via screws 23 onto which there is provided a handle 25, only the horizontally extending portions 24 and 26 being visible in FIGURES 1 and 2. This handle permits the operator of the apparatus to align the tube 20 over pin 18 and envelop roll 8 with cylinder 2. On the surface of cylinder 2 is rigidly affixed housing tube 28 through which passes rod 30 on which at the end proximate window 4 of which there is affixed protruding element 32 suitably constructed of phenolic laminate. This element is provided with reciprocal threads 34 to receive the threads 36 at the end of rod 30. Rod 30 is provided with a handle 38 at the opposite end of threads 36. Handle 38 is reciprocally threaded at 40 to receive threads 42 on rod 30 so that handle 38 is secure and integral with rod 30. Housing tube 28 is securely mounted to cylinder 2 using screws 44, 46, 48 and 50 passing through extension plates 52 and 54 which are integral with housing tube 28. Within housing tube 28 are anti-friction bearings 56 and 58 suitably ball bearings or needle bearings forming part of the tube and positioned against rod 30.

In operation the cylinder 2 of the wrap remover 1 is placed over the roll 8 and snugly over flange 12 by aligning tube 20 over pin 18. Tube 20 provides a guide for enveloping of roll 8 and flange 12 with cylinder 2. The operator holds the cylinder in place by grasping handle 25 with one hand suitably his left hand. With the other hand on handle 38 he manipulates rod 30 within housing tube 28 sliding protruding element 32 to a position between wraps 10 on roll 8 and flange 12. The operator then turns rod 30 about its own longitudinal axis to pass protruding element through open window 4 and in contact with roll 8. He then pulls rod 30 in turned position whereby protruding element 32 engages yarn wraps 10 and deposits them into the unoccupied volume of cylinder 2. The cylinder is then removed from enveloping relationship with roll 8, as tube 20 is removed from over pin 18, the yarn is taken out of the cylinder and rod 30 is adjusted to a suitable starting position.

It is readily seen from the foregoing that I have provided a significantly useful device for removing yarn wraps from rolls particularly rolls revolving at high speeds such as that employed in fiber drawing operations. It is also apparent that my device shields the operator from the revolving roll thus protecting him should the yarn whip about the revolving roll during wrap removal. Other advantages of my invention are obvious to operators who heretofore have been placed in a precarious position when it became necessary to remove yarn wraps from high speed revolving rolls.

The terms and expressions which have been employed are used as terms of description and not of limitation, and there is no intention, in the use of such terms and expressions, of excluding any equivalents of the features shown and described or portions thereof, but it is recognized that various modifications are possible within the scope of the invention claimed.

I claim:

1. An apparatus for removing wraps from a revolving roll comprising a cylinder open at at least one end and adaptable to envelop a roll, said cylinder defining a window

on its side, a scraping means longitudinally slidably positioned on said cylinder and rotatable about its own longitudinal axis, said means having a protruding element adaptable to pass through said window and remove said wraps from said roll into said cylinder and guide means disposed on the surface of said cylinder for positively positioning said cylinder against rotation due to movement of said roll.

2. An apparatus according to claim 1 wherein the scraping means is a rod maintained within a tube rigidly affixed substantially parallel to the surface of the cylinder, said rod being slidable through said tube; said protruding element is a rigid material being softer where it contacts said roll than the surface of said roll; said cylinder is provided

4
with a handle affixed to a plate covering the end of said cylinder opposite the end which envelopes the roll; said guide is an annular tube adapted to snugly accommodate a pin adjacent said roll.
